(57) **CLAIM**

The ornamental design for a interlocking container, as shown and described.

DESCRIPTION

FIG. 1 is a front perspective view of an interlocking container illustrating the new design and showing the design in an open configuration;

FIG. 2 is a front perspective view of the first embodiment of an interlocking container illustrating the new design and showing the design in a closed configuration;

FIG. 3 is a rear perspective view of the first embodiment of an interlocking container illustrating the new design and showing the design in an open configuration;

FIG. 4 is a rear perspective view of the first embodiment of an interlocking container illustrating the new design and showing the design in a closed configuration;

FIG. 5 is a front perspective view of a second embodiment of an interlocking container illustrating the new design and showing the design in an open configuration;

FIG. 6 is a front perspective view of the second embodiment of an interlocking container illustrating the new design and showing the design in a closed configuration;

FIG. 7 is a rear perspective view of a second embodiment of an interlocking container illustrating the new design and showing the design in an open configuration;

FIG. 8 is a rear perspective view of the second embodiment of an interlocking container illustrating the new design and showing the design in a closed configuration;

FIG. 9 is a front view of the first embodiment of the interlocking container of FIG. 1 showing the design in an open configuration;

FIG. 10 is a front view of the first embodiment of the interlocking container of FIG. 2 showing the design in a closed configuration;

FIG. 11 is a rear view of the first embodiment of the interlocking container of FIG. 1 showing the design in an open configuration;

FIG. 12 is a rear view of the first embodiment of the interlocking container of FIG. 2 showing the design in a closed configuration;

FIG. 13 is a top view of the first embodiment of the interlocking container of FIG. 1 showing the design in an open configuration;

FIG. 14 is a top view of the first embodiment of the interlocking container of FIG. 2 showing the design in a closed configuration;

(Continued)

FIG. 15 is a bottom view of the first embodiment of the interlocking container of FIG. 1 showing the design in an open configuration;

FIG. 16 is a bottom view of the first embodiment of the interlocking container of FIG. 2 showing the design in a closed configuration;

FIG. 17 is a right side view of a first embodiment the interlocking container of FIG. 1 showing the design in an open configuration;

FIG. 18 is a left side view of the first embodiment of the interlocking container of FIG. 1 showing the design in an open configuration;

FIG. 19 is a right side view of a first embodiment the interlocking container of FIG. 2 showing the design in a closed configuration; and,

FIG. 20 is a left side view of the first embodiment of the interlocking container of FIG. 2 showing the design in a closed configuration.
